WATERPROOF WALL

Edward J. Walsh, Peekskill, N. Y.

Application July 29, 1935, Serial No. 33,797

2 Claims. (Cl. 72—127)

This invention relates to the waterproofing of walls to the end that water due to capillary action, will be prevented from getting beyond the outer face of a wall, and the invention consists in an improved method for waterproofing the walls as well as in the provision of an improved fabric for use in the waterproofing of the walls.

Among the objects of the invention are, to fulfill a need of waterproofing buildings that have troubled architects and engineers for many years; to provide a method for waterproofing walls which will be more economical and more effective than the methods now generally employed; to obviate the applying of waterproofing on the outside surfaces of buildings built with brick or stone that absorbs water through the brick and mortar joints; and to eliminate application of waterproofing in the form of asphalt or tar base on the inside surfaces of walls.

The invention together with its objects and advantages will be best understood from a study of the following description, taken in connection with the accompanying drawings.

25 In the drawings:

Figure 1 is a fragmentary sectional view through a wall structure illustrating the invention.

Figure 2 is a plan view of one face of a sheet of waterproofing fabric embodying the features of the present invention.

Figure 3 is a similar view of an opposite face of the waterproofing sheet.

Figure 4 is a plan view with a corner portion of one of the layers rolled back to show the asphalt filling.

Figure 5 is a sectional view through the sheet. Referring to the drawings by reference numerals it will be seen that 5 indicates generally a sheet lining which in accordance with the present invention is interposed between the outermost layer 6 of face brick and the innermost layer 7 of brick which layer also includes the usual back-up tile 8. As will be noted, portions of the sheet extend across the back of the sill 8 as well as between the sill and the next adjacent back-up tile 8. It will also be noted that the sheet 5 is also trained around the inner ends of the heading or binding courses of brick 10. Where anchors 11 are used, for example, for anchoring stone, terra cotta or brick facing to the brick back-up wall, I provide at the inner side of the sheet 5 a substantially channel-shaped shield 13 which is apertured to accommodate the anchor 11 as shown in Figure 1. This shield 13 is filled with

cement or other suitable cementitious material 14. Such a shield with its plastic waterproofing material 14 will take care of the puncturing of the sheet 5 caused by the passage of the anchors 11 therethrough and will insure perfect 5 tightness.

The sheet 5 may be made up of a plurality of sections and in Figures 2 to 5 inclusive I have shown a preferred construction of sheet section 5. The sheet or section in the embodiment illustrated consists of facing sheets 15 and 16 respectively. Between these sheets and adhesively uniting these sheets 15 and 16 together is a layer of asphalt 17. In the present instance, the sheet 15 is in the form of thin copper or aluminum sheeting which in addition to being a waterproofing also acts as an insulator, while the sheet 16 is of paper or a suitable paper product.

While a sheet of waterproofing material embodying the features above enumerated, and especially the facing sheet 15 of thin copper sheeting will be found, in actual practice, to be most effective, desirable results can be also obtained from a waterproofing sheet wherein both face sheets are of paper instead of, as in the embodiment illustrated, one facing sheet being of paper 20 while the other sheet is of thin copper sheeting.

Any waterproof sheet consisting of facing sheets with a layer of asphalt therebetween will be found to be impervious to water and consequently when arranged between the different courses of brick and about the heading or binding courses in a manner taught by the present invention and shown in Figure 1, will be found admirably adaptable to the preventing of water 30 working back beyond the face brick 6 of the wall and thus serve the purpose of acting as a non-conductor to the end that the dryness of the inner part of the wall under practically all reasonable conditions will be insured.

Having thus described the invention, what is claimed as new is:

1. A waterproof wall comprising an inner wall structure of brick, an outer wall structure of facing brick, waterproof multiple sheet material interposed between the inner and outer walls, an apertured channel-shaped shield disposed at the side of the sheet material opposite to the outer wall of facing brick with the open side of the channel of the shield disposed against the sheet 45 material, anchoring elements extending through the sheet material and said shield and respectively having their respective opposite ends imbedded in the inner and outer wall structures, and a filling of cementitious material within the 50 55

channel of said shield, as and for the purpose specified.

2. In a wall structure, inner and outer layers of brick, a waterproof multiple sheet member interposed between said inner and outer layers of brick, anchoring elements extending through apertures in said sheet material and respectively

having their respective opposite ends anchored within said inner and outer layers of brick, and means imbedded within the inner layer of brick adjacent the anchor-punctured area of said sheet material for sealing the punctured area of said sheet material. 5

EDWARD J. WALSH.
